E. A. LONG

METHOD OF MAKING BUILDING BLOCKS

Filed June 25, 1925

UNITED STATES PATENT OFFICE.

EDWARD A. LONG, OF NEW CASTLE, PENNSYLVANIA.

METHOD OF MAKING BUILDING BLOCKS.

Application filed June 25, 1925. Serial No. 39,478.

To all whom it may concern:

Be it known that I, EDWARD A. LONG, a citizen of the United States, residing in the city of New Castle, in the county of Lawrence, in the State of Pennsylvania, have invented new and useful Improvements in Methods of Making Building Blocks, of which the following is a full, clear, and comprehensive specification and exposition, being such as will enable others to make the same with exactitude.

The object of my present invention, broadly speaking, is to make certain distinct improvements in concrete building blocks and in the art of making the same, whereby the blocks will be artistic and attractive in appearance, strong and durable in construction, simple in the formation thereof, and which can be manufactured and sold at a comparatively low price.

More specifically stated, my object is to provide a new construction in building blocks wherein the face of the block is given the appearance of bricks or the like, showing the bricks as of a distinct color, and the mortar joints between the bricks as of a color different from the bricks, and both of a color or quality of material different from the body of the building block.

Other objects and particular advantages of my invention will be apparent in the following specification and as shown in the accompanying drawings forming a part thereof.

One method of carrying out the principles of my invention in a practical, economical, and efficient manner is shown in the accompanying drawings, in which—Figure 1 is a perspective view of my facing mold or box, showing the matrix in position therein.

Figure 2 is a perspective view of the mortar space former or grate. Figure 3 is a cross section of a portion of the plate and of the mortar joint former, taken on a greatly enlarged scale. Figure 4 is a horizontal section of one of the completed blocks. And Figure 5 is a face view of one of the completed blocks.

Similar indices denote like parts throughout the several views. In order that the con-

struction, and operation, of the invention may be more fully understood and appreciated, I will now take up a detailed description thereof, in which I will set forth the same as comprehensively as I may.

Facing mold.—This consists of a box-like enclosure, comprising the vertical sides, 1 and 2, and the ends 3 and 4. Said parts rest edgewise on a base 5, to which they are hinged, by means of the hinges 6, whereby they may all be opened out parallel with the base, or be closed together as in Fig. 1, where they are securable in closed position by means of the hooks 7, or otherwise as desired.

Resting on the base 5, and extending thereacross are the two supports 8 and 9, which may be simply blocks of wood or the like.

The matrix.—This comprises a plate 10 adapted to rest on the supports 8 and 9, and of a size such as to fit between the members 1, 2, 3 and 4, substantially as shown. Located on, rising thereabove, and preferably integral with the upper face of the plate 10, are the joint space formers 11 and 12, the former extending longitudinally of the plate 10 and the latter being at right angles to the parts 11. Said joint space formers 11 and 12 are arranged, in this instance, in such manner as to correspond with the size and shape of ordinary bricks, with the cross or vertical joints of each layer of bricks breaking or alternating with the like joints of the layer of bricks next thereto, as in ordinary brick structures. Said members 11 and 12 are formed slightly tapering from their connection with the plate 10 to their tops, or surfaces, which latter are parallel with the surface of the plate 10.

In practice the upper face of the plate 10 may be plain, or it may be roughened, or it may be supplied with various designs, either cameo or intaglio, for instance as shown in my pending applications No. 27295, now in Div. 33; and in my design application, No. D13692.

Mortar space former.—This comprises the longitudinal bars 13, and the shorter bars 14 at right angles thereto, thereby forming a grate-like structure as shown in Fig. 2,

which is substantially identical with the joint space former shown in Fig. 1, with the faces of the various bars 13 and 14 adapted to contact with and fit on the upper faces 5 of the joint space formers 11 and 12.

The method or process of forming blocks is as follows: The matrix is first placed on the supports 8 and 9, and the sides and ends of the mold are then turned up and secured 10 together by the hooks 7, whereby said parts are arranged in the position shown in Fig. 1. The mortar space former, shown in Fig. 2, is then placed in the mold bringing the faces of the parts 13 and 14 into contact 15 with the corresponding faces of the parts 11 and 12, as shown in Fig. 4.

The device as arranged in this instance is to form the front of a concrete block with similitudes of bricks, these being in three 20 superimposed courses alternating laterally with those of the course next thereto.

The material for forming the bricks A is composed of Portland cement, very fine sand, and any desired coloring matter to give the 25 desired appearance thereto when solidified. The above ingredients are mixed together with just enough water to make the mixture hold together. Also the water should be impregnated with enough calcium chloride to strengthen and harden the mass after 30 being molded.

The above mixture, for forming the bricks A, is then put on the plate 10 loose, and then tamped down, bringing the surface thereof 35 even with the tops of the members 13 and 14, and of course covering the plate 10, and filling the spaces between the sides and the ends of the mold and the members 11-12 and 13-14, which would be to the uppermost horizontal line shown in Fig. 4.

The mortar space former (members 13 and 40 14) is then withdrawn upward and laid to one side, and the spaces formed thereby are then filled with a cementitious compost, having a coloring matter which is distinctively 45 different from that of the bricks A, and preferably formed to give the appearance of mortar between the bricks, the said mortar being designated by letter B.

The next step is to provide the backing 50 for the bricks, this is done by filling in a third cementitious composition, designated by the letter C, composed of Portland cement, sand, and brought to the proper workable condition with water added thereto, but without coloring matter. This is tamped down and leveled, and should be roughened on its surface as the main body of the block 55 must adhere thereto when being formed.

The next operation is to loosen the hooks 7, and then turn the sides 1-2 and the ends 3-4 out and down. The plate 10, with the 60 said cementitious elements resting thereon, is then lifted from the supports 8 and 9 and taken to a block forming machine, where

said parts are placed in the bottom of the mold of the block forming machine.

Ordinary concrete grout, formed of Portland cement, gravel, and water, is then filled in on the back surface of the element C, to 70 form the body D of the block being constructed.

Said elements A, B, C and D form an integral construction, as shown in Fig. 3, which completes the block, and when removed from the machine and properly cured or set, it is ready to be used in a wall, which by reason of the several elements involved, as stated, will have the appearance of a brick wall with perfectly formed and finished 80 mortar joints, as shown in Fig. 5.

It is to be understood that I am not to be limited to any particular kind of material or color thereof; and that I am not to be limited to the specific details of construction shown or to the particular method of making the same, but that I am entitled to all the improvements involved which are new and useful and which involve invention. 85

Having now fully shown and described my invention, what I claim and desire to secure by Letters Patent of the United States, is—

1. The art of making concrete blocks, which comprises placing a layer of plastic concrete upon a matrix having certain configurations formed thereon, with a mortar space former corresponding with said configurations and resting thereon, filling in said concrete to the top of said mortar space former, then removing the mortar space former, filling the spaces formed by the mortar space former with concrete of a color different from the first concrete, applying a layer of concrete different from that stated 95 to form a backing, and finally applying concrete different from the others to the face of the last applied layer of concrete to form the main body of the block. 100

2. The method of making building blocks, which consists in providing a mold enclosure, fitting a matrix in said mold, placing a mortar space former on said matrix, filling in concrete to the top of the mortar space former, removing the mortar space former, filling the space formed by the mortar space former with concrete, applying a layer of concrete to form a backing, and then applying concrete to the face of the last mentioned layer of concrete to form the body of 110 a block. 115

3. The method of making building blocks, consisting in providing a mold with the sides and ends thereof opened out, placing a matrix on supports and located in the enclosure formed by the mold, then turning the sides and ends of the mold up and securing them together, placing a mortar space former in the mold and resting on the matrix, placing plastic concrete on the ma- 120 125 130

trix and extending it up to the top of the mortar space former, allowing said concrete to slightly solidify, then removing the mortar space former, filling in the space formed by the mortar space former with plastic concrete of a character different from the first mentioned concrete, applying a layer of concrete of a character different from the two

first mentioned to form a backing, then complete the filling of the mold by applying concrete of a character different from the three first mentioned to form the body of the block, and finally releasing and opening out the sides and the ends of the mold. 10

EDWARD A. LONG.
